UNITED STATES PATENT OFFICE

HUGO SCHMEISSER, OF SUHL, GERMANY

MAGAZINE FOR MACHINE PISTOLS

Application filed February 26, 1931, Serial No. 518,512, and in Germany February 27, 1930.

My invention relates to detachable magazines for machine pistols and more particularly to an improved construction of the magazine body and the plunger-like follower adapted to be actuated by the usual feeding spring and upon which the cartridges rest.

According to the present invention the inward bent upper edges or discharging lips constituting the opening of the magazine for the egress and delivery of the cartridges into the chamber in the breech are reinforced by an U-shaped member or similar formation mounted to laterally embrace the upper end of the magazine body and provided with a recess or the like for securing purposes and with lateral projections or noses forming abutments for limiting the insertion of the magazine body into the holder, while the wall of the tubular magazine body itself is entirely devoid of recesses, projections or the like so that, on the one hand, the discharging lips or orifice of the magazine will be snugly enclosed for protecting and stabilizing purposes, and, on the other hand, the cartridges will readily move in the continuously smooth faced tubular magazine and into the barrel, due to the action of the follower spring, without meeting any obstructions or impediments.

The magazine body, properly speaking, thus is shaped to form a tube of preferably quadrangular cross-section whereof the wall is of uniform thickness and smooth-faced throughout its length, the required projections, recesses or the like for the magazine holder to co-operate therewith being provided on or in the said reinforcing member instead of in the magazine tube itself, as in the prior art, so that the same may be given a greater width or provided with larger cooperating faces and a more reliable seat or cooperation will be secured and loosening of the magazine be prevented thereby even in the event of most heavy shocks which firearms of this type are liable to encounter, as contrasted with the magazines hitherto constructed and devised wherein shoulders, abutments or similar projection for cooperation with the magazine holder are provided immediately in or on the magazine body and, therefore, are

of limited dimensions only in order to not excessively reduce and weaken the wall thereof. Moreover, another advantage of my improved magazine resides in the fact that the reinforcing member or covering affords the possibility of simplifying the construction and manufacture of a magazine of large capacity adapted to receive a plurality of staggered rows of superposed cartridges. At any rate the reinforcement of the discharging lips of the magazine tube together with the simultaneous improvement residing in the continuously smooth faces of the magazine tube devoid of interruptions is the principal object feature and advantage of the present invention.

In some cases I find it of particular advantage to construct and arrange the reinforcing member or covering in a manner that the same will immediately form one of the four wall surfaces of the magazine tube. To this end the two lateral flanges or shanks of the twice bent covering are mounted to overlie and embrace the two flanges or shanks of the similarly U-shaped magazine tube and the cooperating flanges are firmly united by soldering or in any other suitable way. Obviously the manufacture of a magazine of the described type will be greatly simplified and a marked reduction of cost will be attained thereby.

In magazines of large capacity wherein the cartridges are superposed to form two parallel vertical rows in staggered relationship and the uppermost cartridge only is pushed out at a time by the spring controlled follower, it sometimes happens that, at the pushing out operation, the upper-most cartridge engages into the circumferential bottom groove of the shell of the next lower cartridge and causes the latter to be at the same time displaced towards the front side, thereby entailing the danger of loading stoppage.

Another object of the present invention is to remedy this defect. With this purpose in view I provide in the magazine tube a means for causing the uppermost cartridges of the two vertical rows to occupy an inclined position with relation to the cartridges therebelow so that the two uppermost cartridges

will revolve crosswise in their upwards movement. The means employed to this end preferably consists of two pairs of longitudinal ribs of gradually increasing or tapering cross-section, provided on the two opposite side walls of the top end of the magazine tube, the upper ends of the ribs being wider and projecting farther into the room of the magazine tube than the lower ends thereof due to the tapering shape of the ribs. Further the front ribs of the two pairs, that is to say, the two opposite ribs nearest the barrel end of the firearm, are shaped to project to a farther extent into the room of the magazine tube, in accordance with a predetermined ratio, than the rear ribs of the two pairs.

A still further object of the present invention resides in an improved construction of the follower employed in connection with the improved magazine. In the firearms as hitherto constructed or designed a particular element or member is employed for stopping the follower or limiting the number of cartridges to be inserted into the magazine. According to the present invention the follower is provided with downwards extending shanks adapted to guide both itself and the controlling spring and to act at the same time as a stopping means for automatically limiting the number of cartridges to be inserted into the magazine, or in other words, to just strike on the fixed bottom of the magazine tube when in the loading operation the predetermined number of cartridges has been inserted into the magazine. In this way I combine and realize in a very simple, efficient and inexpensive manner the two advantages of automatically limiting the predetermined load and reliably guiding both the follower and the controlling spring during the up and down movement thereof incident to the loading and discharging proceedings.

To the accomplishment of the foregoing and related ends, the invention then consists of the means hereinafter fully described and particularly pointed out in the claims. The annexed drawing and the following description set forth in detail certain mechanism embodying the invention, such disclosed means constituting, however, but one of various mechanical forms in which the principles of the invention may be used.

In said annexed drawings: Figure 1 shows the magazine in side view with the lower end broken away and with the magazine holder indicated by broken or dot-and-dash lines; Figure 2 is a view in vertical section on the line II—II of Figure 1; Figure 3 is a fragmentary side view of a modified form of the magazine with the holder engaging the rear side of the magazine; Figure 4 is a view in horizontal section taken on the line IV—IV of Figure 3; Figure 5 is a fragmentary view of a further modification

of the magazine with the reinforcing member firmly attached thereto to form the rear wall thereof; Figure 6 is a sectional view of the upper part of the modification shown in Fig. 5; Figure 7 is a similar section of the lower part thereof, while Figure 8 is a like section of a modified construction of the reinforcing member interconnected with the magazine; Figure 9 is a view in vertical section of a further modification of the magazine, partly broken off and with the holder or casing carrying the magazine, and the cartridges shown in broken and dot-and-dash lines; Figure 10 is a view in section taken on the line X—X of Figure 9; Figure 11 is a view in longitudinal vertical section of the upper end of the magazine shown in Figure 9 with a few cartridges therein and with the follower removed; Figure 12 is a view in top plan of the parts illustrated in Figure 10; Figure 13 and Figure 14 are front and side elevations, respectively, of the follower constructed according to the present invention; and Figures 15 and 16 are corresponding sectional views of the follower inserted in the bottom end of the magazine.

Referring to the embodiment of the invention shown in Figures 1 and 2 the U-shaped reinforcing member 2 is firmly united with the upper end of the magazine body 1 by soldering or in any other suitable way. The length of the member 2 corresponds to the length of the holding sleeve taken from the top forming the discharging orifice down to the projections or noses 3 formed in the members 2 to act as an abutment or stop for the lower end of the holding sleeve so that the latter will rest thereon when the magazine is fully pushed home, as shown in Figure 1. One wing or shank of the U-shaped member 2 is provided with a comparatively wide recess or aperture 4 for the magazine holder to engage therein while at the same time the two noses 3 act to limit the insertion of the magazine into the holder. In the modification shown in Figures 3 and 4 wherein the holder engages the rear hind edge of the magazine, the rear wall of the magazine tube is shaped to form a longitudinal smooth channelled rib or shoulder for the bottom end of the cartridge shell to freely and smoothly slide thereon. Also in this modification the cartridges thus are prevented from coming in contact with the magazine holder when they are pushed upwards in the magazine by the spring controlled follower, although the holder engages into recesses provided in the one rear corner of both the reinforcing member 2 and the magazine tube.

It will be seen that in both embodiments shown in Figures 1 to 4 wide engaging surfaces may be offered to the magazine holder so that even in case of abnormally long and heavy magazines made of thin metallic sheets

such magazines are safely prevented from accidental disconnection due to concussion or any other shocks a firearm is liable to be exposed. It will further be seen that the 5 magazine holder engages the reinforcing member or covering and not the magazine body itself, so that all disturbing lateral cavities, recesses or grooves are entirely dispensed with in the magazine body and the 10 latter constitutes a smooth faced channel throughout from end to end wherein the cartridges can freely move towards the discharging opening or lips without striking on any impediments or obstacles during the upward movement, with the result that jamming and loading stoppage will be entirely avoided thereby.

In the modifications illustrated in Figures 5 to 8 the U-shaped reinforcing member or 20 covering 5 likewise serves the purpose of bracing the lips 6 of the magazine body 1 and is also equipped with laterally projecting noses or lugs for the holder to abut thereagainst. In these embodiments, however, the 25 U-shaped member or covering 5 is elongated to the full length of the magazine body 1 which is, in cross-sectional regards, likewise of U-shape so as to possess two lateral flanges or shanks leaving one end side open and 30 adapted to be embraced by the flanges or shanks of the reinforcing covering 5, so that when the parts are correctly united, as shown, the covering 5 will form the rear end wall of the magazine.

35 The elongated or lower end of the reinforcing covering possesses two lateral flanges of less width than that of the flanges of the upper part of the covering provided with the projecting noses or lugs, as will be clearly seen on inspection of Figures 6 and 7. In this modification the overlapping flanges of the covering 5 and the magazine body 1 are firmly united by soldering throughout the whole length thereof. In the modification illustrated in Figure 8, however, the flanges of the lower or elongated part of the reinforcing covering 5 are bent twice inwardly and the cooperating flanges of the magazine body are bent twice outwardly so that, when the 50 parts are assembled, the retroverted flanges thereof will engage in and be firmly connected with each other. The upper wider part of the reinforcing covering 5 is firmly united with the magazine body by soldering or 55 welding in both cases shown in the Figures 5 to 8.

In the embodiment shown in Figures 9 to 12 the two rows or columns of staggered cartridges are simultaneously pushed upwards 60 by the spring controlled follower 11, as usually, but the uppermost cartridges of the two rows are automatically and gradually displaced to occupy a, so to say, one row position with the topmost cartridge in the discharging orifice formed by the two rein-

forced lips, whence the topmost cartridge will be discharged, upon firing of a shot, so as to occupy a position in alinement with the bore of the barrel prior to the advance of the cartridge into the barrel. In the embodiment illustrated in Figures 9 to 12 the magazine tube 7 is provided with a pair of guiding ribs 8 and 10 on the inner surfaces of the opposite side walls, said ribs having been produced by a stamping operation so as to be integral with the sheet metal of which the tube 7 consists. The ribs 7 are of tapering form gradually decreasing, as regards width and height, from the top towards the bottom of the magazine, the two rear ribs 8, see Figure 10, being of somewhat less height than the two opposite front ribs 10, for the purpose of gradually displacing the uppermost cartridges automatically from a vertical inclined position into a horizontal 85 slanting position, as will be readily understood upon comparative inspection of Figures 10 and 11. The slanting or crossing position of the three or four uppermost cartridges forming what may be said a single 90 vertical row only, prevents the marginal edges of the bottoms or rims of the cartridge shells from contacting with each other so that when the topmost cartridge is going to be pushed out of the orifice of the magazine, no 95 obstruction can take place and, therefore, no loading stoppage will occur.

As shown in Figures 13 to 16 the follower 100 consists of a substantially U-shaped member 12 whereof the interconnecting median portion or bridge constitutes the follower properly speaking and the two shanks 13 and 14 are shaped to conform to the shape of the magazine tube and to be adapted to embrace and guide the spring of the follower. Preferably I make the follower of a single piece of sheet metal so that the bridge and the shanks thereof are integrally connected with each other and of required rigidity. In order to increase the rigidity and stability of 110 the bridge portion the latter may be corrugated lengthwise, as shown in Figure 16.

In the operation of loading the magazine by inserting cartridges therein, the shanks of 115 the follower strike the bottom 17 of the magazine just when the last one of the predetermined number of cartridges has been inserted so that further cartridges cannot be filled in. The follower thus determines and limits the load and the two shanks 13 and 14 120 thereof act at the same time to properly guide both the controlling spring during expansion or compression and the follower itself in its movements in both directions.

I have herein described and shown several 125 impractical constructions of my present improvements, but it will be apparent that the magazine and its constituent parts are susceptible of embodiment in various other alternative forms, and I, therefore, reserve the 130

privilege of resorting to all such legitimate changes as may be fairly embodied within the spirit and scope of the invention as claimed.

What I claim is:—

- 5 1. A magazine for machine pistols and similar firearms, of the character set forth, comprising a magazine tube with converging lips forming the orifice thereof, a reinforcing covering partially embracing the upper part of said tube inclusive of the said lips, a recess in said covering and noses or lugs projecting outwardly from the said covering for the purpose set forth.
- 10 2. A magazine for machine pistols and similar firearms, of the character set forth, comprising a magazine tube with converging lips forming the orifice thereof, a reinforcing U-shaped covering embracing with its shanks the upper part of said tube inclusive of the said lips, a recess in the one shank intermediate between its two ends, and a nose or lug projecting outwards from either shank, for the purpose set forth.
- 15 3. A magazine for machine pistols and similar firearms, of the character set forth, comprising a magazine body of U-shaped cross-section with converging lips forming the orifice thereof, a reinforcing U-shaped channel member embracing with its two shanks the free ends of the shanks of the said U-shaped magazine body to form a tubular body, a recess in the U-shaped channel member, and a nose or lug projecting outwards from either shank of the latter, substantially as and for the purpose set forth.
- 20 4. A magazine for machine pistols and similar firearms, of the character set forth and as claimed in any of the preceding claims, wherein the reinforcing member or covering is firmly united with the magazine tube or body by soldering or welding.
- 25 5. A magazine for machine pistols and similar firearms, of the character set forth and claimed in claim 3, wherein the upper part of the shanks of the reinforcing member is firmly united with the shanks of the magazine body by soldering or welding and the lower part of both the shanks of the reinforcing member and the shanks of the magazine body have twice bent and retroverted edges engaging with each other for the connecting purpose.
- 30 6. A magazine for machine pistols and similar firearms, of the type set forth, comprising a magazine tube with converging lips forming the orifice thereof, a reinforcing covering partially embracing the upper part of said tube inclusive of said lips, longitudinal tapering guiding ribs on the inner surfaces of the side walls of the upper part of the said magazine tube, a recess in said covering, and noses or lugs projecting outwardly from the latter, substantially as and for the purpose specified.
- 35 7. A magazine for machine pistols and

similar firearms, of the type referred to, as claimed in claim 6, wherein some of the said longitudinal guiding ribs project farther into the room of the magazine tube than the other ones, substantially as and for the purpose set forth.

8. A magazine for machine pistols and similar firearms of the character referred to, comprising a magazine tube with converging lips forming the orifice thereof, a U-shaped reinforcing covering embracing with its shanks the upper part of said tube, a recess in said covering, noses or lugs projecting outwardly from the latter, a spring controlled follower, and shanks connected with the follower and adapted to limit the downward movement of the latter in the said magazine tube, substantially as and for the purpose set forth.

9. A magazine for machine pistols and similar firearms, of the character referred to, as claimed in claim 8, wherein the follower consists of a single piece of sheet metal shaped to form the follower, properly speaking, integral with its shanks.

10. A magazine for machine pistols and similar firearms, of the character referred to, as claimed in claim 8, wherein the part interconnecting the two shanks, that is the follower properly speaking, is provided with longitudinal corrugations for reinforcing purposes.

In testimony whereof, I affix my signature.

HUGO SCHMEISSER.
